UNITED STATES PATENT OFFICE.

ROBERT R. HUGHES, JR., OF UTICA, NEW YORK, ASSIGNOR TO UNION SPECIAL MACHINE COMPANY, OF CHICAGO, ILLINOIS, A CORPORATION OF ILLINOIS.

METHOD OF FORMING CONCEALED STITCHES.

Application filed May 29, 1919. Serial No. 300,650.

To all whom it may concern:

Be it known that I, ROBERT R. HUGHES, Jr., a citizen of the United States, residing at Utica, in the county of Oneida, State of New York, have invented certain new and useful Improvements in Methods of Forming Concealed Stitches, of which the following is a description, reference being had to the accompanying drawing, and to the figures of reference marked thereon.

The invention relates to new and useful improvements in the method of forming concealed stitches—that is, stitches which do not show on the right or face side of the material being stitched.

An object of the invention is to provide an improved method of stitching the folded parts of a fabric or fabric sections, so that the thread from which the loops are formed for uniting certain of the parts will lie within the folded portions thereof and be concealed from view on the face or right side of the fabric.

In the drawings—

Figure 1 is a side view showing the essential parts of a sewing machine arranged for carrying out my improved method;

Figure 2 is a sectional view through the article being stitched, and showing the position of the parts just as the needle is about to enter the material for securing a strip to a body fabric;

Figure 3 is a perspective view showing the manner of guiding and folding the strip which is stitched by my improved method to a body fabric;

Figure 4 is a view similar to Figure 3, but from a different angle and showing the binding strip in section, and in dotted lines the manner of leading the binding strip to the stitching point;

Figure 5 is a sectional view through a fabric and a binding strip secured to the fabric by my improved method of forming concealed stitches;

Figure 6 is a sectional view through a strip folded to form a belt loop and stitched by my improved method of forming concealed stitches;

Figure 7 is a sectional view through a fabric and a tape which is stitched to the fabric by two lines of concealed stitches formed by my improved method of stitching;

Figure 8 is a sectional view showing two

sections of fabric folded and united in part by concealed stitches and in part by through and through stitches of the usual character.

The invention consists broadly in a method of forming concealed stitches which consists in reciprocating the needle of a stitch forming mechanism at an obtuse angle to the plane of the work support, folding and guiding a binding strip about the edge of the body fabric and about the path of the needle, and turning the upper edge portion of the binding strip around and underneath the line of reciprocation of the needle in front of the point where the needle penetrates the materials for stitching, and directing the inturned portion of the binding strip across the path of the needle so that the needle thread will be laid by the needle along the upper face of the inturned portion of the binding strip, formed into loops which pass through the inturned portion of the binding strip, the body fabric and the portion of the binding strip on the opposite face of the body fabric from that entered by the needle.

The invention it is thought will perhaps be better understood by reference in detail to the figures of the drawing which show one way of carrying out my improved method.

In Figure 1 of the drawings, I have shown more or less diagrammatically a feed dog 1, which operates to feed the material underneath the presser foot indicated at 2. Disposed adjacent the presser foot 2 is a fabric guide 3. This fabric guide 3 is formed with an outer guiding wall 4 and an inner guiding wall 5, beneath which is a guiding recess for a fabric strip, which in the present instance, is to be stitched to a body fabric. The fabric strip is indicated at 6 in the drawings and the body fabric is indicated at 9. The guiding walls 4 and 5 are bent around as indicated at 7, so as to fold the edge of the strip. The guiding wall at the opposite edge of the guide may be shaped so as to direct the other edge of the strip for folding the same; or, if desired, said guiding walls may be shaped for folding the edge. The essential feature consists in the infolding or inturning of the edge of the fabric strip at the side of the fabric where the stitches are to be concealed. The stitching needle is indicated at 8 and is arranged so as to move in a line which is at an obtuse angle to the plane of the work support. The normal stitching point is the point where the

needle penetrates the fabric for inserting a loop of the stitching thread through the fabric. It will be noted that the strip 6 is led to the stitching point in the general direction of movement of the needle and with the body portion of the strip at one side of the needle path, while the edge of the strip is folded around to the other side of the needle in the region adjacent the normal stitching point. When the strip passes underneath the presser foot it is directed or deflected at an angle to the path of the needle and the needle will, therefore, penetrate the folded in edge of the strip.

15 Referring more particularly to Figures 3 and 4, it will be noted that the strip has an infolded edge 10 which lies underneath the right side or face portion 11 of the binding strip. Said strip is also carried underneath

20 the body fabric 9, as indicated at 12. The needle 8 passes through the infolded or in-turned edge 10, thence through the body fabric 9, and thence through the portion 12 of the binding strip where the needle loops 25 may be anchored in any suitable way, so as to form single thread chain stitches, or double locked stitches, or said loops may be anchored by a shuttle thread passing directly therethrough forming a lock stitch.

30 The completed article is shown more or less in detail in Figure 5 of the drawings. It will be noted that the binding strip is secured to the body fabric by stitches which are concealed from view on the face or right 35 side of the goods, which is the upper side, as viewed in this figure. The needle thread *n* lies along the edge of the binding strip between the infolded or in-turned edge 10 and the face 11 of the binding strip and the 40 loops *l* go down through the body fabric and the lower face 12 of the binding strip where they are anchored, as above described.

In Figure 6, I have shown the parts of the binding strip stitched together by my improved arrangement of stitching mechanism and folder with the body fabric omitted, thus forming a belt loop. Said belt 45 loop consists of a face portion 13, having inturned or infolded edges 14 and 15, 50 which are overlapped and these edges are united by a stitching thread 16 which lies between the infolded or in-turned edge 14 and the face portion 13 of the strip and the loops formed in the thread by the needle extend 55 downwardly through said inturned or infolded portion 14 and the inturned or infolded portion 15.

In Figure 7 of the drawings, I have shown a tape stitched to a body fabric by two lines 60 of stitches formed by my improved method of making concealed stitches. The tape is indicated at 17 in this figure of the drawings, and is provided at one edge with an infolded or in-turned portion 18 and at the 65 other edge with an inturned or infolded

portion 19. A needle thread 20 lies between the inturned portion 18 and the upper face portion of the tape 17 and the loops extend through this inturned portion and the body fabric, which is indicated at 21. A needle thread 22 lies between the inturned portion 19 and the face of the tape adjacent thereto, and loops formed in this thread pass down through the inturned portion 19 and the body fabric 21. These concealed stitches 75 are formed by folding the edges of the tape about the path of two spaced needles in substantially the manner above described and said tape is led at an angle to the path of the needle at the normal stitching point, so 80 as to cause the infolded portions to cross the path of their respective needles and thereby the stitching thread is passed in loop form through these inturned or infolded portions.

In Figure 8 of the drawings, I have shown two fabric sections secured together in one operation, by two parallel lines of stitching, wherein one of the line of stitching consists of concealed stitches formed in accordance with my invention. One of the fabric sections is indicated at 23 and the other is indicated at 24. The fabric section 23 has an inturned or infolded portion 25. A needle thread 26 lies between this inturned or infolded portion and the fabric section 23 adjacent thereto and is formed into loops which pass through said inturned or infolded portion and through the fabric 24. A needle thread 27 is formed into loops which pass down through the fabric section 23, the inturned or infolded portion 28 of the fabric section 24 and the body of the fabric section 24. These are ordinary through and through stitches.

It will be understood that various other 105 uses may be made of my improved method of forming concealed stitches for uniting folded parts of fabrics or fabric sections. The essential feature of the invention consists in the uniting of the parts in one and the same operation and in the laying of one or more of the threads which unite the parts, so that the thread is concealed by the folded parts of the fabric sections which parts are folded before they reach the stitching point.

110 It is obvious that changes in the details of the steps of the method described may be made without departing from the spirit of the invention, as set forth in the appended claims.

115 Having thus described my invention, what I claim as new and desire to secure by Letters Patent is:

1. The method of stitching a fabric and concealing the stitches in the folded parts of the fabric which consists in forming thread loops by a needle reciprocating in a line at an obtuse angle to the plane of the fabric being stitched, folding and guiding the folded parts of the fabric around the path 125

of reciprocation of the needle, inturning the upper edge portion of said folded parts underneath the line of reciprocation of the needle in front of the point where the 5 needle penetrates the folded parts for stitching, and directing said inturned portion of the folded parts of the fabric and the underneath portion thereof across the path of the needle whereby said inturned portion is 10 stitched to the underneath portion of the folded parts of the fabric and the stitches concealed from view at the upper or face side of the fabric.

2. The method of applying a concealed 15 stitched binding to a body fabric, consisting in forming a series of thread loops by a needle reciprocating in a line at an obtuse angle to the plane of the fabric being

stitched, folding and guiding a binding strip about the edge of the body fabric and about 20 the path of the needle, turning the upper edge portion of the binding strip around and underneath the line of reciprocation of the needle, and directing said edge portion across the path of the needle at the stitching 25 point whereby said needle is caused to penetrate said inturned portion of the binding strip, the body fabric and the portion of the binding strip on the under face of the body fabric.

In testimony whereof I affix my signature in the presence of two witnesses.

ROBERT R. HUGHES, JR.
